UNITED STATES PATENT OFFICE

163,782

HEAT-INSULATED BOTTLE AND LUNCH HOLDER

Edward L. Watkins, Ferndale, Mich.

Application February 6, 1950, Serial No. 7,758

Term of patent 14 years

(Cl. D58—26)

To all whom it may concern:

Be it known that I, Edward L. Watkins, a citizen of the United States, residing in the city of Ferndale, State of Michigan, have invented a new, original, and ornamental Design for Heat-Insulated Bottle and Lunch Holder, of which the following is a specification, reference being had to the accompanying drawing, forming a part hereof.

Fig. 1 is a perspective view of a heat-insulated bottle and lunch holder, showing my new design;

Fig. 2 is a side elevation of the heat-insulated bottle and lunch holder.

The dash line shown in Fig. 1 of the drawing is for illustrative purposes only and represents the upper cap portion of a heat-insulated bottle.

I claim:

The ornamental design for a heat-insulated bottle and lunch holder, as shown and described.

EDWARD L. WATKINS.
